UNITED STATES PATENT OFFICE.

JENS ORTEN BOVING, OF WESTMINSTER, LONDON, ENGLAND.

REFRIGERATING APPARATUS.

Application filed December 22, 1926, Serial No. 156,274, and in Great Britain March 5, 1926.

This invention relates to refrigerating apparatus of the reversing absorption type, that is to say of the type comprising a boiler which contains an absorbent liquid for the 5 volatile refrigerant and a condenser and evaporator for condensing the vapour of the refrigerant driven off from the boiler and for evaporating such liquefied refrigerant, the evaporated refrigerant being subsequently drawn back into the boiler and reabsorbed by the absorbent liquid therein. This action is intermittent, the boiler being at one time heated to drive off the refrigerant vapour whilst the condenser is cooled to condense 15 the vapour, and at another time the boiler is cooled to withdraw the evaporated refrigerant from the evaporator.

More particularly the invention relates to reversing absorption refrigeration apparatus 20 of the kind wherein interruption of the alternative heating of the boiler and the supply of the cooling medium thereto are appropriately automatically controlled by the conditions prevailing in the apparatus.

25 The object of the invention is to provide simple and reliable mechanism which can be set by hand to initiate the heating of the boiler and which, on substantially all the absorbed refrigerant having been driven over into the condenser and evaporator, automatically initiates the interruption of the heating of the boiler and initiates the cooling thereof.

For this purpose, according to the invention, 35 a loaded trip tending to interrupt the heating of the boiler and to cause the supply thereto of cooling medium is supported by a material adapted and arranged to fuse on the increase of temperature which occurs 40 in the boiler when the refrigerant has been driven off. Such trip conveniently is supported by a rod resting on a plug of the fusible material located in a pocket extending into the boiler. Also to avoid the rod 45 becoming set in and held by the fusible material when the latter re-congeals, it is arranged that after escape of the trip, the rod is by spring action, previously overpowered by the superior pressure of the trip, raised 50 out of the fused material.

An apparatus according to the invention is illustrated, by way of example, diagrammatically on the accompanying drawing, in which:—

55 Fig. 1 is a sectional elevation, and Fig. 2 shows details.

a is a boiler which is charged with water and ammonia, or other refrigerant and is adapted to be heated by a gas burner *b*.

The upper portion of the boiler *a* communicates past a non-return valve *c* with a pipe *d*. This pipe *d* leads to a condenser *e*, from whence a pipe *f* leads to an evaporator *g*, into which flows refrigerant liquefied in the condenser *e* from the vaporized refrigerant driven off from the boiler *a* when heated by the burner *b*.

The condenser *e* is cooled by water admitted by a pipe *h* and flowing out by a pipe *i*.

The pipe *d* interconnecting the boiler *a* and the condenser *e* is extended downwards within the boiler *a* to beneath the level of the liquid therein where it is perforated and extends horizontally.

Within the lower portion of the boiler *a* 75 is provided a pipe coil *j*, to which cooling water is admitted by a pipe *k* and from which such water flows out by an outlet *l*.

After approximately all of the refrigerant has been driven off from the boiler *a* and liquefied in the condenser *e* to flow into the evaporator *g*, it becomes necessary to interrupt the heating by cutting off gas from the burner *b* and to cool the boiler by admitting water to the coil *j*. This has the effect of 80 lowering the pressure in the boiler *a* which then exerts a suction on the liquefied refrigerant in the evaporator *g*, causing the refrigerant to be evaporated and withdrawn into the boiler *a*, whilst refrigerating the 85 surrounding medium.

On being drawn into the boiler *a* the vapour of the refrigerant is precluded by the non-return valve *c* from passing directly into the upper portion of the boiler but must 90 bubble from the lower immersed perforated portion of the pipe *d*, through the liquid in the boiler, whereby it becomes absorbed 95 therein.

Now the present invention provides automatically acting means for causing the supply of gas to the burner *b* to become interrupted and for causing the supply of cooling water to the coil *j*, as soon as the refrigerant has been driven off from the 100 boiler. This is effected by means of a trip arm *m* which tends to be angularly displaced by a spring *n*. The trip arm *m* is supported against the tension of the spring *n*, by resting on a collar *o* on a rod *p*. This rod *p* bears 105 on a disc *q* at the head of a rod *g* in alignment therewith, and the lower end of the 110

rod q is stepped on a plug r of fusible material located in a tubular pocket s extending downwards into but having no connection with the interior of the boiler a .

5 The spindle m^1 on which the trip arm m is fast is mechanically connected (see Fig. 2) to a cock t which controls the gas supply to the burner b , and to a cock u which alternatively places the outlet pipe i for the cooling water from the condenser e in communication with a drain pipe v or with the pipe k which admits cooling water to the boiler coil j . When the trip arm m is set so as to be supported by the rods p, q , which can be 10 effected by turning the spindle m^1 by hand by a suitable hand lever (not shown), the gas supply to the burner b is opened by the cock t and the gas can be ignited by a pilot light or otherwise, and the cock u diverts 15 the cooling water to the drain pipe v . Thus, on melting of the fusible plug r which is 20 adapted to occur as soon as the temperature in the boiler a increases as a result of all the refrigerant vapour having been driven 25 off, the rods p, q are forced down by the trip arm m , the nose of which then escapes from the collar o . The trip arm m then turns under the influence of its spring n and by its 30 spindle m^1 turns the cocks t and u so that gas is cut off from the burner b and cooling water is admitted to the boiler coil j .

To raise the rod q before the fusible plug r re-congeals, a spring w in compression is 35 interposed on the rod q between the disc q^1 and the top of the tubular pocket s , which raises the rod q as soon as it is relieved from the thrust of the trip arm m .

To facilitate resetting, the nose of the trip arm m and the under surface of the collar o are appropriately bevelled and the rod p 40 is separate from the rod q .

Whilst in the above described arrangement the condenser e is a separate vessel from the evaporator g , these may be one and 45 the same vessel, in which case a cock would be provided to interrupt the supply of cooling water to such a condenser-evaporator, when the boiler a is being cooled.

Also instead of the gas burner, an electric 50 heater may be employed, the gas cock t being replaced by a rotary or other suitable switch operated by the trip arm m .

I claim:

1. In a refrigerating apparatus of the reversing absorption type, a boiler-absorber, means for heating said boiler-absorber, means for cooling said boiler-absorber, means for controlling said heating and cooling means, a loaded trip operating said controlling means, a pocket extending into said boiler-absorber, a fusible plug located in said pocket, and a rod resting on said fusible plug and supporting said loaded trip. 55

2. In a refrigerating apparatus of the reversing absorption type, a boiler-absorber, means for heating said boiler-absorber, means for cooling said boiler-absorber, means for controlling said heating and cooling means, a loaded trip operating said controlling means, a pocket extending into said boiler-absorber, a fusible plug located in said pocket, a rod resting on said fusible plug, a second rod bearing on said first-mentioned rod, and a collar on said second rod supporting said loaded trip. 60 70 75

3. In a refrigerating apparatus of the reversing absorption type, a boiler-absorber, means for heating said boiler-absorber, means for cooling said boiler-absorber, means for controlling said heating and cooling means, a loaded trip operating said controlling means, a pocket extending into said boiler-absorber, a fusible plug located in said pocket, a rod resting on said fusible plug and supporting said loaded trip, an 80 abutment on said rod, and a spring interposed on said rod between said pocket and said abutment. 85

4. In a refrigerating apparatus of the reversing absorption type, a boiler-absorber, means for heating said boiler-absorber, means for cooling said boiler-absorber, means for controlling said heating and cooling means, a loaded trip operating said controlling means, a pocket extending into said boiler-absorber, a fusible plug located in said pocket, a rod resting on said fusible plug, an abutment on said rod, a spring interposed on said rod between said pocket and said abutment, a second rod bearing on 90 95 100 said first-mentioned rod, and a collar on said second rod supporting said loaded trip.

In testimony whereof I have signed my name to this specification.

JENS ORTEN BOVING.
